(57) **CLAIM**

The ornamental design for a tailsitter aircraft, as shown and described.

DESCRIPTION

FIG. 1 is a front elevation view of a tailsitter aircraft, showing my new design;

FIG. 2 is a rear elevation view thereof;

FIG. 3 is a right side elevation view thereof;

FIG. 4 is a left side elevation view thereof;

FIG. 5 is a top plan view thereof;

FIG. 6 is a bottom plan view thereof;

FIG. 7 is a top, front, right side perspective view thereof;

FIG. 8 is a bottom, front, right side perspective view thereof;

FIG. 9 is a right side elevation view thereof with the landing skid in a state of being spaced apart from the fuselage; and, FIG. 10 is a right side elevation view thereof with the landing skid in a state of being spaced apart from the fuselage and folded out.

1 Claim, 10 Drawing Sheets
